UNITED STATES PATENT OFFICE.

JAMES FRASER, OF WILMINGTON, DELAWARE, ASSIGNOR TO SPEAKMAN COMPANY, OF WILMINGTON, DELAWARE, A CORPORATION OF DELAWARE.

SHOWER VALVE-BODY.

1,330,441.

Specification of Letters Patent.

Patented Feb. 10, 1920.

Application filed December 20, 1918. Serial No. 267,584.

To all whom it may concern:

Be it known that I, JAMES FRASER, a citizen of the United States of America, and resident of Wilmington, in the county of 5 New Castle and State of Delaware, have invented a certain new and useful Improvement in Shower Valve-Bodies, of which the following is a true and exact description, reference being had to the accompanying 10 drawings, which form a part thereof.

My invention relates to valve bodies especially designed for use in connection with shower baths, and it has for its object to provide for a simple and cheap construction 15 especially designed for use where a multiple series of showers are used, my valve body being especially designed for use in connection with two parallel horizontally running hot and cold water supply pipes located at 20 the level of the valve body or bodies.

The nature of my invention will be best understood as described in connection with the drawings in which it is illustrated and in which—

25 Figure 1 is an elevation showing my improved valve body in connection with horizontally running supply pipes, the shower and the pipe running to the shower.

Fig. 2 is a side elevation of the same parts. 30 Fig. 3 is a sectional side elevation of the shower valve body taken as on the irregular line 3—3 of Fig. 4.

Fig. 4 is a front elevation taken on the irregular sectional line 4—4 of Fig. 3, and

35 Fig. 5 is a horizontal sectional view taken on the irregular sectional line 5—5 of Fig. 3.

A and B are the hot and cold water supply pipes which, as shown, are horizontal and parallel to each other and are located at 40 the same level as the valve body. C is the valve body, D the pipe leading from the valve body to the shower indicated at D'.

The valve body is provided with nipples E and F by which it is connected respectively with the pipes A and B, and with a vertical nipple G lying in the same vertical plane, by which it is connected to the shower pipe D. The nipples E and F, as shown, connect with the hot and cold water chambers E' and F', having the parallel overlapping extensions E² and F², which connect

through the ports K and K' with the branches G², G² of the mixing chamber G'. The chambers of the valve body are separated from each other by the webs H, I, I' and I², and the additional webs J and J' in which are formed the ports K and K' leading to the mixing chamber. Valves are, of course, supplied to close and open ports K and K', one such valve being shown at N', 60 Fig. 4, said valve being connected to the valve spindle and handle indicated at N, the valve spindles extending out horizontally from the valve body and extending through the stuffing box chamber indicated at M. 65

It will, of course, be obvious to those skilled in the art that the chamber of the valve body can be extensively modified without affecting its essential features, which are that it should embody a mixing chamber and entrance chambers for hot and cold water and be provided with nipples for direct connection with horizontally running supply pipes and a vertically running delivery pipe situated in the same vertical plane. 70

Having now described my invention, what I claim as new and desire to secure by Letters Patent, is:

1. A shower valve body adapted to be coupled to parallel horizontally running water pipes, arranged one above the other and characterized by having a mixing chamber, a vertical outlet nipple from said chamber for the shower connection, hot and cold water nipples extending from the valve body 80 at different levels in a vertical plane, and each connecting through valve ports with the mixing chamber.

2. A shower plant comprising two parallel horizontally running water supply 90 pipes lying one above the other, in combination with a shower valve body located at the level of the supply pipe and directly connected thereto, said body having a mixing chamber, an outlet nipple for the shower extending from the top thereof, two laterally extending nipples located one above the other and connected to the horizontal supply pipes and valve controlled ported passages connecting the laterally extending nipples 100 with the mixing chamber.

JAMES FRASER.
